COAT RACK

Ian J. Abramson, 3485 W. 15th Ave., Vancouver, British Columbia, Canada, and Charles W. Cawthorne, 6635 Dunblane St., South Burnaby, British Columbia, Canada

Filed Feb. 24, 1970, Ser. No. 21,590

Term of patent 14 years

Int. Cl. D6—04

U.S. Cl. D33—8

Fig. 1.

Fig. 2.

Fig. 3.

Fig. 4.

FIG. 5.FIG. 6.FIG. 1 is a front elevation of a coat rack showing our new design;

FIG. 2 is a top plan view thereof;

FIG. 3 is a rear elevation thereof;

FIG. 4 is a bottom view thereof;

FIG. 5 is an elevation of one end thereof; and

FIG. 6 is an elevation of the end opposite that shown in FIG. 5.

The broken line representation of a coat hanger and retaining chain in the views is for the purposes of illustration only.

We claim:

The ornamental design for a coat rack, substantially as shown and described.
